UNITED STATES PATENT OFFICE.

THEODORE GIBSON, OF TULSA, OKLAHOMA.

GRAIN-CAR DOOR.

1,374,073.

Specification of Letters Patent.

Patented Apr. 5, 1921.

Application filed July 20, 1918. Serial No. 245,923.

To all whom it may concern:

Be it known that I, THEODORE GIBSON, a citizen of the United States, residing at Tulsa, in the county of Tulsa, and State of Oklahoma, have invented new and useful Improvements in Grain-Car Doors, of which the following is a specification.

This invention relates to doors for grain cars and has for its object the provision of 10 a door for closing the door opening in a grain car and comprising a plurality of separately movable sections disposed for vertical sliding movement within track ways disposed at the sides of the door opening and 15 extending upwardly and along the roof of the car whereby the sections may be disposed selectively to close the opening or to be disposed within the portion of the track way at the roof of the car.

20 A very important object is the provision of a door of this character having spring pressed members within the lower portions of the track ways engaging the door sections when in their operative position where- 25 by the door sections will be held firmly against displacement.

Another object is the provision of a door of this character in which the channeled track ways communicate with casings dis- 30 posed at the sides of the door opening, these casings serving as inclosures for the door section engaging members and the leaf springs which urge these members into engagement with the door sections.

35 Another object is the provision of a door of this character provided with means whereby the sections may be locked in raised or lowered positions and having lever operated release and holding means whereby one sec- 40 tion at a time may be lowered while the next succeeding section is held against move- ment.

A further object is the provision of a door structure of this character which will be ex- 45 tremely simple and inexpensive in manufac- ture, easily installed and operated, highly efficient and durable in service and a general improvement of the art.

With the above and other objects and ad- 50 vantages in view, the invention consists in the details of construction to be hereinafter more fully described and claimed and illus- trated in the accompanying drawings in which:—

Figure 1 is a side elevation of a portion 55 of a grain car showing my door in position thereon and in closed position.

Fig. 2 is a cross sectional view on the line 2—2 of Fig. 1 showing the door sections in their inoperative positions by dotted lines. 60

Fig. 3 is a sectional view on the line 3—3 of Fig. 1.

Fig. 4 is an enlarged sectional view on the line 4—4 of Fig. 1.

Fig. 5 is a detail elevation of one end of 65 one of the door sections and

Fig. 6 is an enlarged detail sectional view on the line 6—6 of Fig. 1.

Referring more particularly to the drawings the letter A designates a portion of a 70 grain car provided with the usual door opening B. The jambs at the sides of the door opening are indicated by the letters C and a portion of the roof is designated by the letter D.

In carrying out my invention I provide a pair of casing members 10 disposed against the outer sides of the lower portions of the jambs C and each formed preferably as a single casting having a flange 11 secured 80 upon the jamb C by means of suitable bolts 12. Each casing 10 is provided with a re- cess defined by the walls 13, 14 and 15 and is further provided with a longitudinally ex- 85 tends flange 16 for a purpose to be de- scribed. At each side of the door opening B and communicating with the upper end of the associated casing 10 is a track way 17 formed conveniently of a channel bar which is curved as shown at 18 to extend inwardly 90 of the car for engagement against the roof D.

A plurality of door sections 19 are mount- ed for sliding movement between the guides formed by the casings 10 and the trackways 17. Each door section 19 is formed prefer- 95

ably from a wooden plank 20 and has one longitudinal edge provided with a reinforcing metallic shield member 21 having at its center an outwardly projecting tongue 22. The opposite longitudinal edge of each door 100 section is provided with a similar reinforcing shield 23 having its central portion pro- vided with a groove 24. When the door sec- tions 19 are properly assembled between the guide members they are so disposed that the 105 tongue 22 on one section will engage the groove 24 on the next section. Each door section is further provided at each end with

metallic wear plates 25 flush with the side edges of the shields 21 and 23 and suitably bolted upon the planks 20.

I further provide within each of the casing members 10 a longitudinally extending presser bar 26 formed preferably U-shaped in cross section and having its side flanges disposed between the wall 14 and the flange 16 of the casing. The upper end of the presser bar 26 terminates short of the upper end of the casing 10 and has its upper end curved as shown at 27. A leaf spring 28 is disposed within each casing and extends longitudinally thereof between the presser bar 26 and the wall 15 of the casing. The upper end of each spring 28 is secured to the presser bar 26 by a bolt 29 and the lower end is secured to the wall 15 of the casing by means of a bolt 30 passing through a longitudinal slot 31 in the lower end of the spring. It will thus be seen that the presser bar 26 is resiliently urged toward the wall 13 of the casing.

When the door sections 19 are properly assembled in respect to the guide and are disposed in position to close the opening B, they will be disposed between the presser bars 26 and the walls 13 of the recesses in the casing 10, with their longitudinal edges in engagement with one another. It will be seen that when the door sections are thus arranged the tongues and grooves 22 and 24 respectively on the different sections will be in engagement with one another whereby a tight closure for the opening B will be provided. The pressure of the springs 28 against the presser bars 26 will urge these presser bars 26 into firm engagement with the ends of the door sections 19 so that the top door section will be held firmly against the wall 13 of each casing 10 so as to form a tight joint.

When it is desired to remove the door sections from their obstructing positions in respect to the opening B, it is merely necessary to lift them one by one and slide them upwardly within the casings 10 and the channel bars 17 past the curved portions 18 and into the portions of the channel bars disposed beneath the roof of the car. This position is indicated by dotted lines in Fig. 2 of the drawing. Suitable catches 32 are disposed upon the inner sides of the channel bars 17 adjacent their bent portions 18 for engaging the lower edge of the lowermost door section 19 whereby the sections will be held in their elevated positions. The catches 32 have pivotally connected therewith link members 33 which are in turn connected with crank arms 34 carried by a rod 35 extending transversely of the door opening and provided with a handle 36 and a pointed lateral extension 37. When the sections are in their elevated position and the operator desires to lower them, he grasps the handle

36 and rocks the shaft or rod 35. This movement causes the pointed extension 37 to engage the section next to the lowermost one and hold it against movement, while at the same time the catches 32 are released, allowing the lowermost section to drop into position. This movement of the handle is continued until all the sections are lowered. When the catches 32 are released and the door sections allowed to descend through the guides the curved portions 27 of the upper ends of the presser bars 26 will permit the door sections to enter between the walls 13 of the casings and the presser bars. The provision of the plates 25 upon the ends of the door sections serves to prevent undue wear upon the door sections during their sliding movement.

In order that the sections may be locked in their closed or lowered positions, I provide upon the side of the car adjacent the housings 10, segmental racks 38 engageable by levers 39 pivoted at 40 upon and extending into the housings 10. When the sections are in lowered position, the levers are swung upon their pivots 40 until their ends extend into the housings and engage upon the upper edge of the top section; the levers are then engaged upon the racks so that they will firmly hold the sections against rattling or vertical displacement.

From the foregoing description and a study of the drawings it will be apparent that I have thus provided a door for grain cars formed of a plurality of individually movable sections which may be slid from an obstructing position into a position out of the way beneath the roof of the car.

Having thus described the invention what I claim is:—

1. A door for grain cars comprising a casing disposed at each side of the door opening, the opposing faces of said casings being open and provided with overhanging flanges, guide rails extending from the upper ends of said casings, a plurality of door sections slideable through said guide rails and adapted to be disposed with their ends in said casings, a vertically extending channel bar disposed within each casing in position to bear against said door sections, the upper ends of said channel bars terminating short of the ends of said guide members and being curved outwardly whereby to provide flaring entrance openings for properly guiding the door sections into the space between said channel bars and the opposite walls of said casings, and a leaf spring disposed within each casing and having its lower end secured to the outer wall thereof and its upper end secured to said channel bar whereby to urge the upper ends of the channel bars into close engagement with the uppermost of said door sections.

2. A grain car door comprising guides se-

cured upon opposite sides of the doorway in a grain car, a door structure slidably mounted within said guides, and means for locking said door structure in its locked position comprising a lever pivoted upon each guide and having a nose portion extending through a vertical slot in the guide and engageable with the top edge of the door structure, and a segment secured upon the car wall adjacent each guide in position to be moved over by said lever, said segment having its outer face provided with ratchet lugs selectively engageable by the lever.

3. A grain car door comprising a pair of guides disposed at the sides of the door opening and curved to extend adjacent the roof of the car, a plurality of door sections slidable within said guides, pivoted catch members associated with said

guide members and having projections extending thereinto for engagement by the lower edge of a door section for holding a selected door section in elevated position, a rock shaft journaled transversely of said door opening, crank arms carried by said rock shaft, links connected with said crank arms and said pivoted catch members, a lateral extension on said rock shaft terminating in a prong engageable with the door sections, and a handle on said rock shaft whereby said shaft may be partially rotated whereby said pivoted catch members will be retracted to permit the descent of a door section engaged thereby, said prong engaging the next adjacent door section for holding the same against movement.

In testimony whereof I affix my signature.
THEODORE GIBSON.
